UNITED STATES PATENT OFFICE.

SMITH LEE SANGSTER AND JAMES SANGSTER, OF BURKE'S STATION,
VIRGINIA.

CAR-COUPING.

SPECIFICATION forming part of Letters Patent No. 439,694, dated November 4, 1890.

Application filed March 26, 1890. Serial No. 345,414. (No model.)

To all whom it may concern:

Be it known that we, SMITH LEE SANGSTER and JAMES SANGSTER, citizens of the United States, residing at Burke's Station, in the 5 county of Fairfax and State of Virginia, have invented new and useful Improvements in Car-Couplings, of which the following is a specification.

Our invention relates to car-couplers, and 10 the purpose thereof is to provide simple automatic devices whereby the link-bar may be securely locked at either end in the draw-head, and may be instantaneously released by a person standing upon either side or upon the top 15 of the car, whereby all necessity for entering between the cars either for coupling or uncoupling shall be completely avoided. It is our purpose, also, to provide a simple and novel construction and combination of parts 20 whereby the link-bar may be used either for an automatic coupling-action or in conjunction with the ordinary coupling-pin without any material change in the construction and arrangement of the parts constituting the 25 coupling.

To enable others to practice our said invention, we will proceed to describe the same in detail, reference being had to the accompanying drawings, in which—

30 Figure 1 is a perspective view of the end of a car having our invention embodied therein. Fig. 2 is a horizontal longitudinal section of a draw-head containing our invention. Fig. 3 is a detail perspective showing the cam-shafts by which the locking-blocks are released. Fig. 4 is a detail perspective of the link-bar or coupling-bar. Fig. 5 is a detail perspective of the link-bar, showing a modified construction to allow a coupling with the 40 old link-coupler heretofore in use.

In the said drawings, the reference-numeral 1 denotes the end portion of a railway-car of any ordinary construction, and the numeral 2 designates the draw-head, which, in our invention, is mounted upon and projects centrally from the end of the car in the usual manner. This draw-head consists of a block of metal, of substantially rectangular form, and provided with a longitudinal recess or 45 opening 3 to receive the link-bar, the mouth 50

of said opening being flared or expanded to enable the end of the link-bar to find and automatically enter the same. In each vertical side of the draw-head is formed a horizontal opening 4, which communicates with 55 the longitudinal recess 3. In these openings are arranged rectangular bars or blocks 5 of suitable metal, their vertical faces diverging one from the other, whereby as the outer face is brought flush with the exterior surface of 60 the draw-head the inner face will project increasingly within the channel or opening 3. At the ends adjacent to the mouth of the draw-head these blocks are pivoted upon pins 6, so that they may swing freely in the openings 4, and upon any suitable support are 65 mounted springs 7, which bear upon the exterior faces of the blocks at or near their rearward ends. In these ends are formed vertical recesses 8, within which lie cams 9, mounted 70 or formed upon vertical pins 10, which turn freely in apertures formed in the draw-head, their ends rising above the top of said draw-head and being provided with forked inwardly-projecting arms 12. Between the forked 75 end of each of these arms is pivotally attached the end of a link 13, its other extremity being connected with the end 14 of a vertically-arranged lever 15, which is fulcrumed between lugs 16, the end of said lever extending up as 80 high as the top or roof of the car, or substantially so.

The swing of the blocks 5 is limited in both directions by the ends of the fork formed by the openings 4, which abut against the pins 85 10, carrying the cams 9. By this construction the blocks are normally held with their outer faces substantially flush with the outer faces of the draw-head, while the rear ends of said blocks project within the channel 3. 90

The numeral 17 denotes the link-bar, which consists of a bar of iron having a vertical width in excess of its horizontal thickness. Upon the ends of said link-bar are formed heads 18, having a thickness about double 95 that of the body of the bar and provided with vertical shoulders 19 on each, which engage the inwardly-projecting ends of the swinging blocks 5. The heads of the link-bar are beveled off above and below and on both sides to 100

aid it in entering the draw-head. In each head is formed an aperture 20, with which an ordinary coupling-pin may engage, said pin lying in an opening 21 in the draw-head.

5 In order to operate the coupling to disconnect the link-bar when the operator is standing upon the ground and at the same time to avoid the necessity of entering between the cars, I mount upon the end of the car, behind 10 the lever 15, a rock-shaft 22, having a crank-arm or cam-yoke 23, and provided also with levers 24, which are rigid with the ends of the rock-shaft. It will be seen that by revolving said shaft the end of the lever 15 will be 15 thrown outward, turning the cam-pins 10 and swinging the blocks 5 outward, thus releasing the link-bar.

Coupling is effected by simply entering either head of the link-bar within the opening or recess 3, its entrance spreading the blocks 5 until the head 18 has passed the ends of the blocks, which instantly snap inward in front of the shoulders 19 on the head of the link-bar.

25 What I claim is—

1. In a car-coupling, the combination, with a draw-head mounted on the car, of blocks arranged in channels in the side walls of the draw-head and pivoted at their outer ends, 30 said blocks having faces diverging from each other from their pivotal points toward the car, springs by which said blocks are thrown inward and their inner faces caused to enter the link-bar channel of the draw- 35 head, and vertical pins or shafts lying in apertures in the draw-head and having cams which spread the said blocks and release the link-bar, substantially as described.

2. In a car-coupling, the combination, with 40 a draw-head mounted on the car and having a longitudinal channel to receive the link-bar,

of blocks pivoted at their outer ends in longitudinal channels in the sides of the draw-head, said blocks having their inner faces entering the link-bar channel at an angle to its 45 axis, springs drawing or throwing said blocks inward, pins or shafts lying in apertures in the draw-head and having cams lying in recesses formed in the ends of said blocks, links pivoted at one end to oppositely-projecting 50 arms on the cam pins or shafts and pivoted at their other ends upon the extremity of a vertical lever fulcrumed upon a horizontal bearing on the end of the car, the power end of said lever rising substantially to or nearly 55 to the top of the car, substantially as described.

3. In a car-coupling, the combination, with a draw-head having a channel for the link-bar, of blocks pivoted at their outer ends in horizontal recesses in the side walls of the draw-head, said blocks having shoulders at their free ends engaging shoulders on the head of the link-bar, vertical cam pins or shafts lying in apertures in the draw-head and having 65 cams lying in recesses in the ends of the blocks, links pivotally connected at one end to oppositely-extending arms on the cam pins or shafts and connected at their other ends to the end of a vertical lever fulcrumed on 70 the end of the car, and a rock-shaft mounted behind said lever and having a crank or cam adapted to act thereon and provided also with levers at each end accessible from the sides of the car, substantially as described. 75

In testimony whereof we have affixed our signatures in presence of two witnesses.

SMITH LEE SANGSTER.
JAMES SANGSTER.
